UNITED STATES PATENT OFFICE.

CYRIL DOUGLAS McCOURT, OF LONDON, ENGLAND, AND CARLETON ELLIS, OF MONTCLAIR, NEW JERSEY, ASSIGNEES, BY MESNE ASSIGNMENTS, TO SURFACE COMBUSTION, INC., OF WILMINGTON, DELAWARE, A CORPORATION OF DELAWARE.

APPARATUS FOR MAKING NITROGEN AND CARBON DIOXID.

1,289,496.

Specification of Letters Patent. Patented Dec. 31, 1918.

Application filed January 26, 1912, Serial No. 673,572. Renewed May 18, 1918. Serial No. 235,392.

To all whom it may concern:

Be it known that we, CYRIL D. McCOURT, a subject of the King of Great Britain, and resident of 45 Braxted Park, Streatham Common, London, England, and CARLETON ELLIS, a citizen of the United States, and resident of Montclair, county of Essex, and State of New Jersey, have made certain new and useful Inventions Relating to Improvements in Apparatus for Making Nitrogen and Carbon Dioxid, of which the following is a specification, taken in connection with the accompanying drawing, which forms a part of the same.

This invention relates to apparatus for making nitrogen and carbon-dioxid, for instance, by the combustion of explosive mixtures of gaseous fuel and air preferably in substantially the proportions required for the complete combustion of the fuel so as to produce products of combustion containing only relatively small proportions of the combustible material or of the supporter of combustion therefor. The carbon-dioxid may be separated from such products of combustion as by absorption in a suitable carbonate liquor system in which potassium or sodium carbonate solution is circulated to absorb carbon-dioxid from the combustion gases and to liberate the same when the carbonate liquor is heated as by the heat from the combustion producing the gases, for instance, and the carbon-dioxid may be utilized by drying and compressing into liquid form. The decarbonated gases may be purified to the desired extent and the resulting nitrogen fixed as by conversion into cyanamide or utilized in other ways.

In the illustrative form of apparatus shown diagrammatically in the drawing one or more boilers or evaporating devices 35 may be used provided with the desired number of heating tubes 38 containing or packed with refractory combustion accelerating material 37, such for instance, as granular fire-clay magnesite or other material of about one-half or one inch mesh. Any suitable explosive gaseous mixture formed by the mixture or incorporation of a combustible gas or vapor or mixture thereof with air or other supporter of combustion preferably in about the proportions required for the complete combustion of the combustible material may be injected or brought into contact with the

heated refractory material to effect the accelerated surface combustion of the explosive gaseous mixture therein as described more fully in the patents of Bone, Wilson and McCourt, such as their United States Patent No. 1,015,261 of January 16, 1912. This may be effected by forcing air and producer or coal gas through the two gas and air pipes 39 so that the desired mixture is secured and forced into the refractory material 37, thus causing accelerated surface combustion to occur therein to effect the intense and substantially complete combustion of the fuel, thus producing combustion gases which may with proper regulation of the proportions of gas and air contain only a fraction of a per cent. of excess oxygen or of combustible material. The combustion gases especially where a suitable gasometer is interposed in the gas supply system may be readily produced with an excess of oxygen not exceeding one or two per cent., that is, there may be an excess of oxygen in the combustion gases to an extent less than the percentage indicated or the oxygen excess may be nil and there may be a slight excess of combustible components in the gases. Many other means of effecting the substantially complete and preferably accelerated combustion of gaseous or other fuel may be used, as for instance by burning combustible gases under considerable pressure or burning fuel of various kinds under conditions of intense heat in the presence of substantially the theoretical amount of air or other supporter of combustion so as to secure combustion gases with preferably an excess of oxygen not exceeding a few per cent. For example, one or more diaphragm combustion units may be used in this way, the porous refractory diaphragm 45 being indicated as mounted within a suitable casing of iron or the like having a facing 44 of mica or other suitable material to allow the transmission of heat from the diaphragm. A suitable mixture of explosive gases may be supplied to the diaphragm through the gas and air supply pipes 43 in which the valves 42 may be arranged to secure the proper mixture preferably containing substantially theoretically correct proportions of air and combustible gas or vapor for complete combustion. As described in the British and United States patents and applications of Bone, Wilson

and McCourt the refractory diaphragm may be formed of granules of porous refractory material, such as firebrick of substantially uniform size chosen in accordance with the 5 explosive gases to be burned therein and united by calcining with a small proportion of relatively fusible material into a homogeneous diaphragm an inch or an inch and a half thick or so and having a network of 10 irregular sectioned small gas passages therethrough. When the discharge face of the diaphragm is heated in any desired way the explosive gases fed through the diaphragm are ignited and normal conditions are shortly 15 established under which the explosive gases burn with accelerated substantially flameless combustion within the outer or discharge layer of the diaphragm.

50 shows another boiler containing one or 20 more heating tubes 47 adapted to contain suitable granular combustion accelerating material so as to effect the surface combustion of explosive gases supplied under the desired pressure of several ounces or so by 25 suitable injecting means such as the gas and air pipes 53. The liquid 49 within this boiler may be water and its evaporation may produce steam which may be collected in the steam dome 51 and supplied through the 30 steam pipe 52 for power purposes or the like. The combustion gases in this case are indicated as passing into a suitable water heater or economizer 48 which may be generally similar in construction to that shown in the 35 Bone, Wilson and McCourt Patent No. 1,015,131 of January 16, 1912 so as to utilize a considerable proportion of the heat of the combustion gases for the heating of the boiler feed water or other purposes. The 40 cooled combustion gases may then be drawn through the exhaust pipe 47 connected with the gas pump 46 which forces them through a suitable pipe 23. The combustion gases from the diaphragm heating units may when 45 the valves 59 are open pass through the pipe 29 and be forced by the gas pump 24 into the pipe 23 and this gas pump may also receive or draw the combustion gases from the 50 boiler or heater 35 through the economizer or water heater 28 so as to force all the combustion gases in the combustion system illustrated into the pipe 23.

Suitable cleaning or washing devices may 55 be used to preliminarily remove undesirable elements, such as any sulfur dioxid that may be present in the combustion gases and for this purpose suitable washers, such as 18, 20 may be used containing a relatively small 60 amount of water or other fluid 21 which may be slowly circulated therethrough by any desired means so as to substantially completely absorb the sulfur dioxid from the combustion gases as they percolate up through the 65 water on being discharged from the pipe 22.

The pipe 19 leads into a similar second washer 18 where a similar percolating action may take place, the washed combustion gases passing through the regulating valve 17 and pipe 15 into any suitable absorption device 9 which may be in the form of a tower of the desired height packed with coke or other suitable material 10 over which any suitable absorption liquor may be allowed to flow. The absorption or carbonate liquor 75 may be an aqueous solution of any suitable absorbent of carbon-dioxid, as for instance a ten to thirty per cent. solution of potassium or sodium carbonate or other available salt. This carbonate liquor may be supplied from 80 the liquor tank 13 through the pipe 11 in amounts regulated by the liquor feed valve 12 so as to trickle down through the absorption device and be extensively brought into contact with the combustion gases fed therethrough preferably in the opposite direction to the flow of the carbonate liquor so that the carbonate liquor discharged from the absorption device through the pipe 16 having the valve 30 contains a large amount of bi-carbonate. By heating this carbonate liquor 85 in any desired way carbon-dioxid may be liberated therefrom and the bicarbonate correspondingly transformed into carbonate for reabsorption of additional amounts of gas. 90 This may be conveniently effected by heating the carbonated liquor by heat evolved in the production of the combustion gases, as for instance by passing the carbonate liquor through the pipe 26 communicating with the 100 heater or economizer 28 when the valve 58 is opened so as to heat this liquor to a considerable extent before it passes through the pipe 41 into the boiler 35, although of course by opening the valve 25 and closing the valve 105 58 the carbonate liquor may flow through the bypass around the economizer 28 and directly into the pipe 41. This liquor 36 is considerably raised in temperature in the boiler 35 and the available carbon-dioxid 110 largely or completely driven therefrom so as to be taken from the dome 27 by the pipe 32. This carbon-dioxid may be dried in any desired way as by passing it through a suitable drier 31 and the gas may then be compressed in any compressing apparatus, such for instance, as the three-stage compressor 33 so as to make the carbon-dioxid available 115 in compressed or liquefied form for commercial purposes. The restored carbonate liquor 120 may be taken from the boiler or heater 35 by the pipe 40 and forced by the circulating pump 34 through the pipe 14 into the liquor tank 13 from which it may again circulate through this carbonate liquor system as described. 125

The decarbonated combustion gases delivered preferably through a pipe 8 from the absorption device under a slight pressure above that of the atmosphere to prevent in- 130

ward leakage may be purified or freed from any undesirable component such as the slight excess of oxygen or combustible gas by passing the same through a suitable purifier 6. By using cuprous chlorid, hot copper oxid, etc., in this purifier any traces of combustible material, such as carbon-mon-oxid may be eliminated or rendered harmless, or if the decarbonated combustion gases 10 contain a slight excess of oxygen this may be eliminated therefrom by using hot finely divided copper in the purifier. The gases from the purifier may pass through the pipe 5 when the valve 55 is open so as to pass 15 through the connected pipe 4 into any suitable converter for utilizing or fixing the nitrogen. The combustion gases may, however, pass directly from the absorption device to the converter when the valve 55 is 20 closed and the bypass valve 7 is opened so as to directly connect the pipes 8 and 4. The converter may be of any desired form, such for instance, as the converter tank 2 through which passes a suitable heating ele- 25 ment 1 in the form of a carbon rod through which electricity may be passed to supply heat in the desired amounts to the granular carbid 3, for instance, contained within the converter, such material absorbing nitrogen 30 to form cyanamid when the proper conversion temperature has been reached.

Having described this invention in connection with an illustrative form of apparatus, parts, devices, materials, arrangements 35 and orders of steps, to the details of which disclosure the invention is not of course to be limited, what is claimed as new and what is desired to be secured by Letters Patent is set forth in the appended claims:

1. Apparatus for producing nitrogen and carbon-dioxid, comprising a boiler provided with a tube or tubes extending through the liquid space of the boiler and packed with granular refractory material, means for injecting into the granular refractory material within the tubes an explosive gaseous mixture of fuel gas and air in substantially combining proportions to effect accelerated surface combustion of the explosive mixture 45 and to heat said boiler, an economizer to receive the combustion gases from the boiler and cool the same, an absorption device to which the cooled combustion gases are delivered, and means for circulating carbonate liquor through said absorption device and then through said economizer and said boiler to cause carbon-dioxid to be absorbed from the combustion gases by the carbonate liquor in the absorption device and to heat 50 the carbonate liquor in the economizer and in the boiler to drive off carbon-dioxid therefrom.

2. Apparatus for producing nitrogen and carbon-dioxid, comprising a boiler having 55 a furnace portion provided with a bed of

granular refractory material, means for injecting into said bed of refractory material an explosive gaseous mixture of fuel gas and air in substantially combining proportions to effect surface combustion of the explosive mixture and to heat the boiler, an economizer to receive the combustion gases from the boiler and cool the same, an absorption device to which the cooled combustion gases are delivered, and means for 70 circulating carbonate liquor through said absorption device and then through said economizer and said boiler to cause carbon-dioxid to be absorbed from the combustion gases by the carbonate liquor in the absorption device and to heat the carbonate liquor in the economizer and in the boiler to drive off carbon-dioxid therefrom.

3. Apparatus for producing nitrogen and carbon-dioxid, comprising a boiler having 85 a furnace portion provided with a bed of granular refractory material, means for injecting into said bed of refractory material an explosive gaseous mixture of fuel gas and air in substantially combining proportions to effect surface combustion of the explosive mixture and to heat the boiler, an absorption device to which the combustion gases are delivered, and means for circulating carbonate liquor through said absorption device and then through said boiler to cause carbon-dioxid to be absorbed from 90 said combustion gases by the carbonate liquor in the absorption device and to heat the carbonate liquor in the boiler to drive off carbon-dioxid therefrom.

4. Apparatus for producing nitrogen and carbon-dioxid, comprising a boiler, means for effecting accelerated surface combustion of fuel gas and air in substantially combining proportions and to thereby heat the boiler, an economizer to receive the combustion gases and to cool the same, an absorption device to which the cooled combustion gases are delivered, and means for circulating carbonate liquor through the absorption device and then through the economizer and the boiler to cause carbon-dioxid to be absorbed from the combustion gases by the carbonate liquor in the absorption device 100 and to heat the carbonate liquor in the economizer and in the boiler to drive off carbon-dioxid therefrom.

5. Apparatus for producing nitrogen and carbon-dioxid, comprising a boiler, means 120 for effecting accelerated surface combustion of fuel gas and air in substantially combining proportions and to thereby heat the boiler, an absorption device to which the combustion gases are delivered, and means 125 for circulating carbonate liquor through said absorption device and then through the boiler, to cause carbon-dioxid to be absorbed from the combustion gases by the carbonate liquor in the absorption device and to heat 130

the carbonate liquor in the boiler to drive off carbon-dioxide therefrom.

6. Apparatus for producing nitrogen and carbon-dioxide, comprising means for effecting accelerated surface combustion of an explosive gaseous mixture of combustible gas and air in substantially combining proportions, an absorption device to which the combustion gases are delivered, means for 10 circulating carbonate liquor through the absorption device to absorb carbon-dioxide from the combustion gases, and means for heating said carbonate liquor by heat developed by said combustion to drive off carbon-dioxide therefrom.

7. Apparatus for producing nitrogen and carbon-dioxide, comprising means for effecting combustion of fuel gas and air in substantially combining proportions, means for 20 cooling the combustion gases, an absorption device to which the cooled combustion gases

are delivered, means for circulating carbonate liquor through the absorption device to absorb carbon-dioxide from the combustion gases, and means for heating said carbonate 25 liquor by heat developed by said combustion to drive off carbon-dioxide therefrom.

8. Apparatus for producing nitrogen and carbon-dioxide, comprising means for effecting combustion of fuel gas and air in substantially combining proportions, an absorption device to which the combustion gases are delivered, means for circulating carbonate liquor through the absorption device, and means for heating the carbonate liquor 30 by heat developed by said combustion to 35 drive off carbon-dioxide therefrom.
